GAS TURBINE PLANT

Walter MacTavish Ogston, Dumfries, Scotland,
assignor to Power Jets (Research and Development) Limited, London, England, a British company

Application August 12, 1949, Serial No. 109,841
In Great Britain August 27, 1948

1 Claim. (Cl. 60—39.17)

1

This invention relates to improvements in gas turbine plant when applied to the generation of hot gas under pressure. More particularly the invention is concerned with the case where working fluid exhausted from a gas turbine imparts heat indirectly through a heat exchanger to a pressurised gas stream, such an arrangement being adopted, for example, when it is desired to generate a hot high pressure stream of air or other gas with its oxygen content conserved and which cannot therefore be heated by having fuel burnt in it. The invention is envisaged as having particular application to the formation of a hot air blast for blast furnace operation but may be also applied wherever a stream of hot compressed gas is required.

As is known, the usual method of heating air for use as an air blast in a blast furnace is to burn a portion of the blast furnace exhaust gas and to pass the hot products of combustion produced thereby for a given period through one of two regenerative heat exchangers of the "Cowper" stove or chequer brick type, after which the supply of hot gas is transferred to the other stove while cold air is passed through the hot stove to be heated on its way to the blast furnace. The flows of hot gas and cold air are reversed after a certain period and these alterations are continually repeated.

One disadvantage of such an arrangement is that due to the substantial pressure of the cold air above atmospheric there is a considerable loss in heat when the two gas flows are reversed. A further disadvantage is that the above-mentioned stoves are necessarily very large and consequently very costly.

One object of the present invention is to avoid these disadvantages and accordingly the invention provides a generator of hot high pressure gas comprising means for supplying pressurised gas, a continuously operable heat exchanger for receiving and indirectly heating said pressurised gas supply, means for supplying hot gas to said heat exchanger to effect such heating comprising a multi-stage gas turbine from which the hot gas supply is derived at an intermediate pressure stage, which stage is so selected that the hot gas pressure is similar to that of the gas to be heated thereby.

The heat exchanger is preferably of the regenerative kind and comprises a rotary disc or drum containing a matrix having a large number of small axial or radial channels respectively through which the two gas streams flow in opposite directions. It is well known that heat ex-

2

changers of this type have in general, important advantages in respect to bulk and efficiency compared with heat exchangers of other kinds, but have the attendant disadvantage that effective sealing against leakage between the respective gas streams is difficult to achieve and maintain; however, the difficulty is minimised when the gas streams are at similar pressures, and it is this condition which the invention is intended to bring about. In a preferred form of the invention intended particularly for use in blast furnace operation, the gas to be indirectly heated is air which is compressed in a compressor driven by the turbine rotor. Preferably this compressor is a multi-stage one from which the air to be heated is taken off at an intermediate stage, while air for the turbine working fluid is taken off at the final stage. The latter, in the particular application to blast furnaces, is burnt with blast furnace exhaust gas as the fuel, which is first raised to an appropriate pressure by a gas compressor mounted on the same shaft as the main compressor.

Preferably the hot gas stream is derived from the outlet of one high pressure stage turbine coupled to a second low pressure stage turbine and both driving the compressor. The hot gas from the outlet of the high pressure turbine may be burnt with additional fuel before it passes through the heat exchanger and this fuel may also be blast furnace gas derived from an intermediate stage of a multi-stage gas compressor.

After passing through the heat exchanger, the gases pass through the second or low pressure turbine from the outlet of which they pass directly to atmosphere or through an auxiliary heat exchanger, which may be of the tubular recuperative type, for heat exchange with air to be used as blast air and derived from an intermediate stage of the air compressor.

By way of example one embodiment of the preferred form of the invention is now described in detail with reference to the accompanying drawing which represents schematically the plant arrangement of a hot high pressure gas generator for supplying blast air to a furnace. The plant includes a low pressure compressor stage 1, a high pressure compressor stage 2, a high pressure turbine stage 3 and a low pressure turbine stage 4 all mounted on the same shafting so that the two turbine stage rotors drive the two compressor stages.

Air from the atmosphere enters the low pressure compressor stage 1 and, when discharged therefrom is divided, a proportion of the air being

taken through an auxiliary heat exchanger 5 for heat exchange with hot exhaust gases leaving the low pressure turbine stage 4, and subsequently to a main rotary regenerative heat exchanger 6 from which the air, being both pressurised and heated, passes to the tuyères of a blast furnace 7. The remainder of the air discharged from the low pressure compressor stage 1 passes to the high pressure compressor stage 2 and thence to a combustion chamber 8 where it supports the combustion of a fuel; the combustion products pass to the high pressure turbine stage 3 and then to a reheat combustion chamber 9 where more fuel is burnt, before passing successively through the main heat exchanger 6, the low pressure turbine stage 4 and the auxiliary heat exchanger 5, and finally exhausting to atmosphere.

Fuel economy in the plant is effected by utilising a portion of the blast furnace exhaust gases as fuel for heating purposes. Thus, these gases are collected at the furnace upstages 10 and, after suitably cleaning and cooling, are led to a two-stage gas compressor 11, 12 which is driven by the main turbo-compressor rotor; after compression in the low pressure stage 11 a proportion of the fuel gas is bled off and delivered to the reheat combustion chamber 9, while the remainder is fully compressed in the high pressure stage 12 of the gas compressor and is delivered to the combustion chamber 8.

An electric power generator 13 is also driven from the turbo-compressor shaft and provides an outlet for surplus power produced in the plant; provision may also be made for "motoring" this generator in order to start the plant, using power previously accumulated.

If the plant is arranged for normal operation on a constant pressure cycle, that is, for combustion in each of the combustion chambers 8 and 9 to take place without a substantial variation in gas pressures, it is apparent that by selecting similar pressure ranges for the high pressure compressor and turbine stages 2 and 3 respectively, a low or negligible pressure differential in the heat exchanger 6 is ensured. Furthermore, the high pressure stage 12 of the fuel gas compressor may be similarly selected so that both the fuel and the combustion-supporting gases are supplied at similar pressures to each of the respective combustion chambers.

Although the invention is of particular advantage for use with a rotary regenerative heat exchanger, due to the elimination of the necessity for pressure resistant gas seals and so making possible high rotary speed, it also presents advantages when used in combination with a recuperative heat exchanger, for example, of the tu-

bular type since, due to the pressure of the air and gas flows being approximately equal, the walls of the tubes may be relatively thin and will therefore be less costly and lighter.

5 I claim:

Gas turbine power plant for supplying a blast of hot air under pressure suitable for use in a blast furnace, including a low pressure compressor stage supplying at an intermediate pressure both blast and other air, a high pressure compressor stage receiving said other air from said low pressure compressor stage and delivering it at a higher pressure, a high pressure turbine stage and a low pressure turbine stage driving said high and low pressure compressor stages, a combustion chamber receiving said other air from said high pressure compressor stage and supplying combustion products to said high pressure turbine stage, and a heat exchanger, of the type having a continuously moving element transferring heat between independent gas streams, receiving on the one hand blast air from said low pressure compressor stage to be heated and on the other hand combustion products from said high pressure turbine stage to heat the blast air, said combustion products being delivered thereafter to said low pressure turbine stage, the intermediate pressure of the combustion products during heat exchange being not greatly different from that of the blast air so that leakage between their independent stream in the heat exchanger tends to be minimized.
